UNITED STATES PATENT OFFICE.

JOHN B. MORGAN, OF PHILADELPHIA, PENNSYLVANIA.

DESIGN FOR WOVEN FABRIC.

SPECIFICATION forming part of Design No. 23,839, dated December 4, 1894.

Application filed October 29, 1894, Serial No. 527,356. Term of patent 7 years.

To all whom it may concern:

Be it known that I, JOHN B. MORGAN, a citizen of the United States, residing in Philadelphia, Pennsylvania, have invented a certain 5 Design for Ticking and other Woven Fabrics, of which the following is a specification.

My design for ticking or other woven fabric is clearly illustrated in the accompanying drawing.

10 The main feature of the design is the arrangement of the narrow and wide stripes and the particular design of each stripe.

J is the wide stripe and K the narrow stripe. The stripe J is a well defined stripe composed of three shaded stripes j^3 and three narrow light stripes j . At one side of the shaded stripes and beyond the white stripes are narrow dark stripes j' and on one side of the wide stripe J is a dark stripe j^2 . At one side of each 15 dark stripe is a shaded stripe j^1 .

The narrow stripe K has two well defined dark stripes k and a wide central stripe k' composed of three tinted stripes and beyond the dark stripes are two light stripes k^2 .

In the back ground L near each narrow 21 stripe K are two very narrow tinted stripes l , the whole giving the effect clearly illustrated in the accompanying drawing.

I claim—

25 The design for woven fabric as herein described and clearly shown in the accompanying drawing.

In testimony whereof I have signed my name to this specification in the presence of two subscribing witnesses.

JOHN B. MORGAN.
